UNITED STATES PATENT OFFICE.

JOSEPH L. MILLER, OF JERSEY MILLS, PENNSYLVANIA.

METALLIC TIE.

1,213,122.

Specification of Letters Patent.

Patented Jan. 16, 1917.

Application filed June 24, 1916. Serial No. 105,629.

To all whom it may concern:

Be it known that I, JOSEPH L. MILLER, a citizen of the United States, residing at Jersey Mills, in the county of Lycoming and State of Pennsylvania, have invented new and useful Improvements in Metallic Ties, of which the following is a specification.

This invention relates to improvements in the construction of metallic ties for railway 10 rails, and the primary object of the invention is to produce a device of this character which shall be of a simple, cheap and thoroughly effective construction wherein the rails will be seated on suitable cushion 15 members, the said tie having means associated therewith and forming a part thereof for securing the rails thereon.

With the above and other objects in view, the improvement resides in the construction, 20 combination and arrangement of parts set forth in the following specification and falling within the scope of the appended claims.

In the drawing: Figure 1 is a side elevation of a tie constructed in accordance with 25 the present invention illustrating rails thereon. Fig. 2 is a top plan view of the same, Fig. 3 is a central vertical longitudinal sectional view through the same, Fig. 4 is a transverse sectional view approximately on 30 the line 4—4 of Fig. 2, and Fig. 5 is a perspective view of one of the cleats.

My improvement contemplates the employment of two substantially similar metallic box-like members which provide the 35 ends of the tie proper. These end members, indicated by the numerals 1, have open tops and have either integrally formed with or secured to their bottoms each a pair of spaced longitudinally arranged cleats 2. 40 The cleats, in the showing of the drawings are illustrated as detachable members and each has its underface, from its ends, cut away or reduced and the said ends provided with longitudinal slots 3 which are centrally 45 arranged in the said cleats. By this arrangement it will be noted that a space is left between the end members of the cleats at the bottom of the box sufficient to permit of the insertion of the heads 4 of bolt members 5 50 through the slots 3 of the cleats, and the said slots are of a sufficient width to receive therein the square or rectangular portions 6 of the shanks of the bolts provided next to their heads 4. This arrangement prevents the 55 bolts from turning. The pairs of cleats in each of the box-like ends of the ties are

spaced a sufficient distance to receive therebetween longitudinally arranged substantially rectangular cushion blocks 7, and it is upon these blocks that the base flanges of 60 the rails 8 rest. The bolt members, it will be noted, may be moved longitudinally of the cleats so as to permit of their shanks engaging or contacting with the opposite edges of the base flanges of the rail 8. The sides of 65 the box members 1 are depressed from the upper edges thereof, as indicated by the numerals 9, the width of the said depressions corresponding with the width of the base flanges of the rails 8 and the depth of the 70 depressions being sufficient to permit of the upper faces of the cushion blocks 7 being disposed approximately centrally of the said depressions to extend above said depressions, and thus it will be noted that the rails rest 75 directly upon the blocks 7 and do not, except for the edges of their flanges, engage with the metallic end members or boxes 1.

Each of the boxes 1, after the cushion members have been arranged therein is 80 adapted to receive a filler 10 which may be of any desired nature, but is preferably in the nature of a preservative for the wooden cushion members 7, and in the device disclosed by the drawings the filler 10 is in the 85 nature of cotton waste which has been thoroughly saturated with oil, the said oil being adapted to impregnate the cushion block 7 and thus materially add to the life 90 of the same. It may be here stated that the blocks may be readily removed should the same become worn.

The end walls of the box members 1 have their upper edges centrally grooved as at 11 to receive the tongues 12 of closure plates 95 13. The inner and lower edges of the closure plates 13 are beveled, as at 14, to agree with the upper surfaces of the base flanges of the rails 8 against which they lie, and the closure plates 13 may be of a length to permit of their said inner edges contacting with the webs of the rails. The closure plates are provided with suitable openings through which the threaded shanks of the bolt members 4 pass and securing elements, in the nature of nuts 15, engage with the projecting 100 ends of the bolts and bind against the upper faces of the closure plate 13, thus effectively securing the rails upon the ties.

The referred to end walls of the box 110 members 1 have their lower corners provided with outwardly extending bracket members

16 which have alining openings and which are adapted to receive a rod member 17 that connects the two box-like ends of the tie. The rod member 17 may have its central portion of a substantially rectangular shape, as indicated by the numeral 18 in the drawings, but it is obvious that the rod may pass through a central tube as indicated by the numeral 19 in the drawings and still again 10 the rod, at a suitable distance from its ends, may be provided with lugs 20, indicated by the dotted lines in Fig. 2 of the drawings which may be either rigidly secured to the said rods or may be adjustably arranged 15 thereon. The central member of the rods is adapted to contact with the inner ears of the box-like members 1 to hold the said ends in proper spaced relation with each other and the outer ends of the rods have thread- 20 edly secured thereon nuts 21 whereby the rod members are effectively connected with the ends and the ends retained in proper spaced relation with each other.

It is to be understood that the metal rods are 25 of sufficient inherent resiliency as to permit either of the ends 1 of the tie yielding under the pressure of the load of the rolling stock passing thereover, and from the foregoing it is believed that the construction and ad- 30 vantages of the device will be perfectly ap- parent to those skilled in the art to which such invention appertains without further detailed description.

Having thus described the invention, what 35 I claim is:

1. A tie for railway rails, comprising hollow end members, rods connecting said members, a cushion block providing a seat for the rail in each of said end members, 40 closure plates for the end members, and means for securing the closure plates upon the end members and over the base flanges of the rails.

2. A tie for railroad rails, comprising hol-

low end members having open boxes, rods 45 connecting the end members, a cushion block providing a seat for a rail in each of the end members, closure plates for the end members, longitudinally disposed elements in the ends contacting with the sides of the cushion 50 blocks, and securing means associated with the said elements and engaging the closure plates for locking the closure plates upon the said ends and in engagement with the rails.

3. A tie for railroad rails having metal boxes forming the ends thereof, rod members at the lower portions of the boxes for connecting the same, a cushion block providing a seat for a rail in each of the boxes, 60 a filler of preservative material between the cushion blocks and the ends of each of the boxes, cleats secured in the boxes and contacting with the sides of the blocks, closure plates for the boxes arranged to have their 65 confronting edges overlying the base flanges of the rails when the rails are arranged upon the cushion blocks, and locking means removably connected with the cleats and passing through the closure plates for locking 70 the said plates upon the said boxes.

4. In a metallic tie for railway rails, hollow members having open tops providing the ends of the ties, ears at the lower corners of the ends, rod members passing 75 through the ears, means for securing the rod members, a spacer element upon each of the rod members between the ends, a cushion block providing a rail seat in each of the ends, closure plates for the ends, elements 80 secured to the bottom plates of the boxes and contacting with the sides of the cushion blocks, bolt members removably associated with said elements and having their threaded ends passing through openings in the 85 closure plates, and nuts for the bolts.

In testimony whereof I affix my signature.
JOSEPH L. MILLER.
